(57) **CLAIM**

The ornamental design for a cellular flip phone, as shown and described.

DESCRIPTION

FIG. 1 is a front, top, and right side perspective view showing our new design for a cellular flip phone in an open position.

FIG. 2 is a front, top, and right side perspective view showing our new design for a cellular flip phone in a closed position.

FIG. 3 is a left side elevated view of the cellular flip phone of FIG. 2.

FIG. 4 is a top plan view thereof.

FIG. 5 is a front elevated view thereof.

FIG. 6 is a rear elevated view thereof.

FIG. 7 is a right side elevated view thereof.

FIG. 8 is a bottom plan view thereof.

FIG. 9 is a front, top, and right side perspective view of the cellular flip phone shown in FIG. 1 in an open position without the broken line showings; and,

FIG. 10 is a bottom plan view of the cellular flip phone shown in FIG. 1 without the broken line showings.

The broken line matter in the drawings is for illustrative purposes only and forms no part of the claimed design.
